Primary Examiner — Bridget L Eland**CLAIM**

The ornamental design for a mobile phone, as shown and described.

DESCRIPTION

FIG. 1 is a back perspective view of a mobile phone showing our new design;

FIG. 2 is a front view of the mobile phone of FIG. 1;

FIG. 3 is a back view of the mobile phone of FIG. 1;

FIG. 4 is a top view of the mobile phone of FIG. 1;

FIG. 5 is a bottom view of the mobile phone of FIG. 1;

FIG. 6 is a right side view of the mobile phone of FIG. 1; and,

FIG. 7 is a left side view of the mobile phone of FIG. 1.
